(57) **CLAIM**

The ornamental design for a stud for buildings, as shown and described.

DESCRIPTION

FIG. 1 is a front perspective view showing my new design for a stud for buildings;

FIG. 2 is a right side elevational view for the stud for buildings;

FIG. 3 is a front elevational view for the stud for buildings; FIG. 4 is a left side elevational view for the stud for buildings;

FIG. 5 is a rear elevational view for the stud for buildings; FIG. 6 is a top plan view for the stud for buildings;

FIG. 7 is a bottom plan view for the stud for buildings; and, FIG. 8 is a cross sectional view taken along lines 8-8 of FIG. 4 for the stud for buildings.

The stud for buildings is shown with a symbolic break in its length. The appearance of any portion of the article between the break lines forms no part of the claimed design.

1 Claim, 2 Drawing Sheets
